UNITED STATES PATENT OFFICE.

LE ROY A. CRUMLEY, OF NEW YORK, N. Y., ASSIGNOR TO J. H. WHITE MANUFACTURING COMPANY, OF BROOKLYN, NEW YORK, A CORPORATION OF NEW YORK.

DESIGN FOR A LANTERN PANEL.

Application filed March 9, 1927. Serial No. 21,072. Term of patent 3½ years.

To all whom it may concern:

Be it known that I, LE ROY A. CRUMLEY, a citizen of the United States, residing at the borough of Manhattan, in the city, county, and State of New York, have invented a new, original, and ornamental Design for a Lantern Panel, of which the following is a specification, reference being had to the accompanying drawing, forming part thereof.

Figure 1 is a front elevation of a lantern panel showing my new design, and

Fig. 2 is a fragmentary top view of the same.

I claim:

The ornamental design for a lantern panel as shown.

LE ROY A. CRUMLEY.
